Primary Examiner — Carol P Rademaker(74) *Attorney, Agent, or Firm* — Armstrong Teasdale LLP(57) **CLAIM**

The ornamental design for a rocket bottle, as shown and described.

DESCRIPTION

FIG. 1 is a front elevational view of a rocket bottle in accordance with the present invention;

FIG. 2 is a rear elevational view thereof;

FIG. 3 is a right side elevational view thereof, the left side elevational view being a mirror image except for the unclaimed threads;

FIG. 4 is a top plan view thereof;

FIG. 5 is a bottom plan view thereof; and,

FIG. 6 is a top, front, right side perspective view thereof.

The broken lines shown in the drawings of a pour spout and threads are included for the purpose of illustrating environmental structure and form no part of the claimed design.
